AIR CONDITIONING

Stewart Clark Coey, Glen Ridge, N. J., assignor
to Research Corporation, New York, N. Y., a
corporation of New York

Application November 27, 1936, Serial No. 113,059

17 Claims. (Cl. 62—129)

This invention relates to a method and apparatus for conditioning air or other gases. It is directed particularly to means whereby the factors of chemical absorption, evaporative cooling and heat exchange are utilized in a simple and effective manner to control the temperature and humidity conditions in a body of air or other gas. The invention provides a system of air conditioning involving ordinary pressures and temperatures therein. Refrigeration resulting from subjecting vapors to cycles comprising compression and expansion is not required.

While air conditioning includes in its scope the removal of suspended matter and undesirable gases and vapors other than water vapor from the air, and the present invention provides for these factors to the extent required in practice, the invention is aimed primarily at the control of temperature and humidity conditions and will be more particularly described with reference to the maintenance of the air in an enclosure at summer comfort conditions for human beings.

The invention utilizes streams of a heat transfer fluid, commonly water, to remove heat from a gas to be conditioned by passing the fluid in indirect heat exchange relationship with the gas while its moisture content is being lowered by means of a moisture removing agent, and thereafter transferring the heat taken up by the fluid from the gas being conditioned to gas leaving the conditioned space in the form of latent heat by evaporatively cooling a fluid by direct contact with the gas leaving the conditioned space. The lowering of the wet bulb temperature of the gas may be effected in a variety of ways, as for example, by contacting the gas with a moisture absorbing fluid such as a solution of calcium chloride, lithium chloride, sulphuric acid, phosphoric acid or the like, or by contacting the gas with solid moisture absorbing agents, such as solid calcium chloride, silica gel or activated alumina. The removal of heat from the gas by the heat transfer fluid may be effected by using the heat transfer fluid to cool the moisture absorbing agent, or to cool the gas during or succeeding the moisture absorption, or to transfer the heat from the gas in part by cooling the moisture absorbing agent and in part by cooling the gas itself. In each case the heat exchange between the gas and the heat transfer medium is indirect in the sense that the gas and the heat transfer medium do not come into direct contact.

In a preferred embodiment of the invention the heat transfer fluid is divided into a plurality

of circuits. The moisture-absorption-cooling unit and the evaporative cooling unit are divided into a like number of sections. The water cooled in the first section of the evaporative cooler where it comes in heat exchange relationship with the withdrawn air at its lowest wet bulb temperature is brought into heat exchange with the entering air in the last section of the absorber-cooler where it removes from the air the final increment of heat to bring it to the desired dry bulb and wet bulb temperatures.

The water cooled in the last section of the evaporative cooler where it is cooled by the last increment of available latent heat capacity of the air leaving the system is brought into heat exchange relationship with entering air in the first section of the absorber-cooler where it removes from the air the initial increment of heat.

The invention will be more particularly described with reference to the accompanying drawings, in which:

Fig. 1 is a diagrammatic representation of an air conditioning system embodying the principles of the invention;

Fig. 2 is a diagrammatic representation of one specific embodiment of the invention;

Fig. 3 is a diagrammatic representation of a modified embodiment of the invention;

Fig. 4 is a diagrammatic representation of another modification of the invention;

Fig. 5 is a heat flow diagram illustrating the principles of the invention;

Fig. 6 is a heat flow diagram illustrating the principles of the invention under different conditions of operation from those of Fig. 5; and

Fig. 7 is a diagrammatic representation of a further specific embodiment of the invention.

In the diagrammatic representation of the invention shown in Fig. 1, the air to be conditioned is passed through a conditioning unit A and into the space to be conditioned by means of fan M, and is drawn out of the air conditioned space and through heat exchanger B by means of fan N. Cooling water is circulated through conditioning unit A and heat exchanger B by means of pump O. In conditioning unit A the air is subjected to the action of means for removing moisture whereby its dew point is lowered. As stated above, the removal of moisture may be effected by means of liquid or solid moisture absorbing agents with which the air is brought into direct contact. Heat is removed from the air in the conditioning operation by indirect heat exchange with the circulating water. This may be effected, for example, by contacting the mois-

30

ture removing means, or the air itself, or both, with the heat exchanger P through which the cooling water is circulated.

In heat exchange unit B the water is cooled by the evaporative cooling effect of the air coming from the air conditioned space in direct contact with all or a portion of the circulating water and/or in direct contact with a stream of water which is in heat exchange relationship with the circulating water.

In this manner the latent heat capacity of the air leaving the conditioned space is utilized for cooling, by indirect heat exchange, the air passing to the conditioned space, whereby the dry bulb temperature of the entering air may be reduced to a temperature approaching, within the limits of effective heat exchange differentials, the wet bulb temperature of the leaving air, with a minimum loss of water by evaporation.

In the specific embodiment shown in Fig. 2, the conditioning unit A includes the finned cooling coils A₁ and A₂, and the heat exchange unit B is in the form of an evaporative cooler, including finned coils B₁ and B₂.

Atmospheric air is drawn into conditioner A at 1, by means of fan 2 which blows the conditioned air leaving A into the space to be air-conditioned through conduit 3. Air in equivalent amount is withdrawn from the air conditioned space through conduit 4 by means of fan 5 which causes the air to pass successively over the lower part of coil B₁, the upper part of coil B₁, and coil B₂ and thence to the atmosphere through 6.

In passing over coils A₂ and A₁ in conditioner A the air is dehumidified by the absorption of moisture by means of deliquescent liquid, such as, for example, a solution of calcium chloride, lithium chloride or the like flowing down over

the coils in direct contact with the air. The moisture absorbing liquid is collected in sump 7 and is continuously recirculated over the coils by means of pump 8. At the same time the sensible heat of the air is reduced and the latent heat of absorption removed by means of the coolant liquid circulating in the interior of coils A₂ and A₁.

The moisture absorbing agent may be maintained at the proper concentration by recirculating at least a part of it through concentrator C, wherein it is caused to flow over a finned heating coil 9 and a stream of air is blown over it by fan 10. The supply of steam or other heating medium to coil 9 is regulated by means of valve 11 which is controlled by humidostat 12 in conduit 3. By suitably setting the humidostat the concentration of the moisture absorbent can be maintained at such a point as to reduce the humidity content of the air to any desired constant amount, for example, 40% relative humidity.

The particular moisture absorbing agent and the particular method of reconcentrating it described above are purely illustrative and other dehumidifying agents and other means for maintaining the moisture absorptive properties of such agents may be substituted.

The absorption of heat necessary to bring the air to the desired dry bulb temperature is effected in conditioner A by means of cooling fluid, such as water, circulated through coils A₁ and A₂. This cooling medium cools the air indirectly by the absorption of the necessary amount of heat from the moisture absorption medium flowing over the outside of the coils.

The heat absorbed by the cooling medium circulating through coils A₁ and A₂ is transferred in cooler B to the air withdrawn from the conditioned space. The air is still necessarily of an effective wet bulb temperature substantially lower than its dry bulb temperature and can therefore absorb a considerable amount of heat, as latent heat. This transfer of heat to the outgoing air in the form of latent heat is effected in the embodiment of Fig. 2 by an evaporative cooling operation. In this operation the coolant liquid is cooled, either directly or indirectly, by the evaporation of water in direct contact with the air. For example, the whole amount of water to be cooled may be brought, in an extended surface condition, into direct contact with the outgoing air. The contact is maintained to the extent necessary to bring the air to substantial saturation or to such lower degree of saturation as is economically justified.

In the system shown in Fig. 2, the cooling is effected by direct evaporative contact of the air with a portion of the water flowing over the outside of finned coils B₁ and B₂ which in turn absorb heat from a further portion of the water flowing inside the tubes thereby lowering its temperature.

The effectiveness of the system is increased by circulating the cooling water in two separate circuits. The water in one circuit is subjected to the cooling effect of the outgoing air at its lowest wet bulb temperature in coil B₁, wherein its temperature is brought by means of the evaporative cooling of the water flowing outside the coils to nearly the wet bulb temperature of the air entering the cooler. This water is circulated by means of pump 13 to coil A₁ of the conditioning unit where it brings the dry bulb temperature of the air down to the desired point.

The water in the other circuit is brought into indirect heat exchange, in coil B₂, with water flowing over the outside of the coil and being evaporatively cooled by the residual latent heat capacity of the outgoing air coming from coil B₁. The water cooled to an intermediate temperature in coil B₂ is circulated by pump 14 to coil A₂ of conditioner A where it serves to absorb a primary increment of heat from the absorption agent in contact with the incoming air.

It will be seen, therefore, that in this embodiment of the invention successive increments of heat absorbed from the incoming air are successively transferred in inverse order to the outgoing air, or, in other words, successive increments of temperature drop obtained by the evaporative cooling effect of the latent heat capacity of the outgoing air are successively transferred to the incoming air. In this way the over-all temperature drop obtainable without the use of refrigeration is substantially increased.

That portion of the water in cooler B which is caused to flow over the outside of the coils is advantageously withdrawn from the lowest temperature circuit and carried to the top of the cooler by pipe 15 as shown in Fig. 2. In this case both the external stream of water and the water flowing through coil B₁ are collected in sump 16, whence it is withdrawn by pump 13. The make-up water necessarily supplied to the system to replace the relatively small amount evaporated in cooler B may be supplied to the sump 16 through float valve 17. This has the advantage that when the water available from the mains is at a lower temperature than that of the circulating water the make-up water tends

to further lower the temperature of the water in the low temperature circuit.

It is also possible to maintain the water circulating circuit or circuits between cooler B and conditioner A entirely closed, and continuously recirculate a separate body of water over the outside of the coils in the cooler, adding to this, of course, the necessary amount of make-up water to replace that evaporated.

10 The embodiment of the invention shown in Fig. 3 likewise includes an air conditioner E, with finned coils E₁ and E₂, and an evaporative cooler F, with finned coils F₁ and F₂.

Air entering the system at 21 is drawn by fan 23 successively over coils E₂ and E₁, then out through spray eliminator 22 and through conduit 24 to the space to be conditioned.

Air from the conditioned space is drawn by fan 25 through conduit 26 into cooler F, where it passes successively over coils F₁ and F₂ and through outlet 27 to the atmosphere.

The moisture absorbing agent is pumped successively over coils E₁ and E₂ by means of pump 28. Its concentration is maintained at the desired point by means of concentrator D wherein medium withdrawn from the system by conduit 29 is passed through finned coils 30 and then sprayed through distributor 31 over finned coil 32. Increase in air flow over coil 32 by fan 33 increases the rate of evaporation of water from the absorbing agent. The heated concentrated absorbing agent flows from coil 32 over the outside of coil 30 where it is cooled by the agent flowing to the concentrator and at the same time preheats the inflowing absorbing agent. The concentrated agent is returned to sump 34 of conditioning unit E through conduit 35.

The low temperature coolant circuit in this embodiment includes coil F₁, distributor 36, sump 37, pump 38, coil E₁, and coil 39. Coil 39 is situated in the sump of conditioning unit E and removes a further amount of heat from the moisture absorbing agent before it is circulated over the coils E₁ and E₂.

45 The higher temperature coolant circuit, which utilizes the last increment of latent heat capacity of the outgoing air and transfers to it the first increment of heat absorbed from the incoming air, includes coil F₂, pump 40 and coil E₂.

50 When the latent heat capacity of the outgoing air is not entirely sufficient to bring the cooling water down to the necessary temperature to attain the desired temperature conditions in the air condition space, an additional cooling effect may be obtained by drawing a quantity of atmospheric air or air whose wet bulb temperature has been lowered by artificial means through cooler F. This is advantageously effected by admitting the desired amount of air into the cooler through conduit 41 and causing it to pass over coil F₂.

55 It may under some circumstances be advantageous to obtain a portion of the desired cooling by utilizing the evaporative cooling effect of atmospheric air, for example, by circulating a portion of the cooling water through an evaporative cooling tower through which atmospheric air is passed, or by passing a certain amount of air through the same cooling tower with the air leaving the conditioned space.

60 The embodiment of the invention shown in Fig. 4 illustrates the use of a solid agent for the removal of moisture from the air.

75 The air conditioning unit G includes heat ex-

change members G₁ and G₂, shown as finned coils. A solid moisture adsorbing agent 51, such as lump calcium chloride, silica gel, activated alumina and the like, is maintained in the conditioning unit adjacent or surrounding the heat exchange members. The rest of the system is shown by way of example as being identical with the corresponding portion of Fig. 2, the same reference characters being used for corresponding elements.

Air drawn through louvres 52 by means of fan 23 is brought into contact with the moisture absorbing agent 51. The latent and sensible heat of the air are removed in successive increments by indirect heat exchange with the cooling water 5 in heat exchange members G₁ and G₂. The water supplied to heat exchange members G₁ and G₂ is cooled in cooler F to successively lower temperatures by the evaporative cooling effect of the air leaving the conditioned space as is explained more fully in connection with the preceding figures.

In the embodiment of the invention shown in Fig. 7, the cooling liquid circuits are maintained more entirely independent than in the embodiment of Fig. 2, for example, while the flow of moisture absorbing agent in the conditioning unit is fully countercurrent to the flow of cooling liquid. In the embodiment of Fig. 7, the air conditioning unit H includes finned cooling coils H₁ 23 and H₂, which form part of circuits through which cooling water is circulated between coil H₁ and coils J₁ and J₂ of evaporative cooling tower J, and between coil H₂ and coils J₃ and J₄ of the evaporative cooling tower.

Air is drawn into conditioner H at 71 by means of fan 72 which blows the conditioned air leaving H into the space to be air conditioned through conduit 73. Air in equivalent amount is drawn from the air-conditioned space through conduit 74 by means of fan 75 which causes the air to pass successively over coils J₁, J₂, J₃ and J₄ and thence to the atmosphere through spray eliminator 76. The moisture absorbing agent is sprayed over coils H₁ and H₂ in a direction countercurrent to the flow of cooling water and concurrent to the flow of air over the coils and is collected in sump 77. The moisture absorbing agent is maintained at the proper concentration by circulating at least a portion of it through concentrator K wherein it first passes through coil 78 in the collecting sump 79 of the concentrator where it removes a portion of the heat content of the liquid in the sump. The absorbent then passes through coil 80 where it is further warmed by heat exchange with the air and vapor leaving the evaporator and is sprayed out of sprayer 81. It then passes successively over packing material 82, for example, Raschig Rings, steam coil 83 and packing material 84 and thence into collecting sump 79.

The heat absorbed in the cooling water in coils H₁ and H₂ is transferred in cooler J to the air withdrawn from the conditioned space. This transfer takes place at two separate temperature levels in the lower and upper portion of the cooling tower, respectively. A portion of the cooling water from coil H₁ is passed successively through coils J₂ and J₁, while the other portion of the water is caused to flow over the outside of the coils from distributor 85. Both portions of the water are collected in sump 86 and returned to the circuit. The water from coil H₂ is similarly passed through and over coils J₄ and J₃ in the upper portion of the tower, the external flow of 75

water being distributed at 87 and both portions of the water being collected at 88.

By this method of operation it is possible to cool the water in the circuit supplying coil H₁ to a somewhat lower temperature than when all of the water flowing over the outside of the coils is derived from the low temperature circuit, as shown in Figs. 2, 3 and 4, while a more efficient cooling and dehumidifying effect is obtained by 10 circulating the moisture absorbing agent counter-current to the flow of the cooling liquid in the conditioning unit.

Figs. 5 and 6 diagrammatically illustrate the heat flow and temperature levels in an embodiment of the invention in which the heat transfer medium is comprised in two circuits.

In Figs. 5 and 6, conditions in the conditioner unit are shown on the left and conditions in the evaporative cooler are shown on the right of the figures. The passage of the fluids through these heat exchange devices is measured, in relation to distance or time, or both, horizontally across the diagrams, although no numerical values are shown. Temperatures may be read off the vertical scale at the left of the figures. The diagonal lines indicate temperature changes in the fluids as they pass through the heat exchangers.

In the absorber-conditioner, all heat absorbed from the air, either as latent heat or sensible 30 heat, is finally transferred through the walls of the heat exchange members to the cooling water as sensible heat and the critical values in this exchanger are the dry bulb temperatures. In the evaporative cooler, where at least a portion of the cooling water is in direct contact with the air, the cooling water can be cooled only to the wet bulb temperature of the air as a limit and the wet bulb temperatures are the critical temperatures in the evaporative cooler.

40 In the diagram of Fig. 5, atmospheric air enters the system at 95° F. dry bulb, 75° F. wet bulb, and 67° F. dewpoint. In the first stage of conditioning the air is cooled to 85° F. dry bulb and the wet bulb temperature is reduced to about 67° F., the cooling water in circuit No. 2 entering this stage at 81° F. and leaving at 84.5° F. In the next stage the air is cooled to the desired dry bulb temperature of 75° F. and wet bulb temperature of 60° F., the cooling water in circuit No. 1 entering this stage at 71° F. and leaving at 74.5° F.

45 In passing through the air-conditioned space the air attains a wet bulb temperature of 66° F. at which condition it enters the evaporative cooler. In the first stage of the cooler, temperature of the water in circuit No. 1 is decreased from 74.5° to 71° F., while the wet bulb temperature of the air is increased to 73° F. In the second stage the water temperature in circuit No. 2 is decreased from 84.5° F. to 81° F., the wet bulb 50 temperature of the air increasing to 79.5° F.

55 The shaded areas H_{a1} and H_{a2} between the dry bulb temperature line u , and the lines j_1 and j_2 indicating the temperature changes in the cooling water in circuit 1 and circuit 2, respectively, represent the amount of heat transferred from the air to the cooling water in these circuits as the water passes through the absorber-conditioner unit. The shaded areas H_{e1} and H_{e2} between the wet bulb temperature line w and the lines g_1 and g_2 indicating the temperature changes in the cooling water in circuits 1 and 2, respectively, represent the amount of heat transferred from the water in these circuits to the air passing through the evaporative cooler. The vertical distances between the temperature lines

represent temperature gradients and the greater the gradient the greater will be the amount of heat transferred to or from a given amount of water with a given heat transfer surface. The vertical arrows indicate the direction of heat flow. 5

The areas on the right do not correspond with the areas on the left of Figs. 5 and 6 in part because of the fact that the air as it leaves the conditioned space and enters the evaporative cooler has a considerably higher wet bulb temperature than it had when leaving the absorber-conditioner unit due to the respiration of people and other conditions in the conditioned space, and in part because of the differences in operating conditions of the two heat exchange units. The 15 slightly shaded area H_{e3} in Fig. 5 represents the effect of the heat received by the air in passing through the conditioned space upon the performance of the evaporative cooler, which heat is carried to atmosphere by the air in addition to the 20 heat, represented by areas H_{e1} and H_{e2}, given up to the air by the cooling water as the air passes through the evaporative cooler.

The temperatures and areas shown on the graphs are values selected from data obtained with apparatus of the character described and represent practice wherein space, cooling surfaces, water and power are used economically. Changes in the areas of the surfaces of the cooling coils and in the amount of water pumped 30 through them will change the position and slope of the temperature lines somewhat.

The graphs also indicate the advantage in dividing the stream of water used in transferring heat into two circuits as compared with the results obtained with a single circuit. Assuming that the water in circuits 1 and 2 is combined and will be returned to the evaporative cooler at intermediate temperature y (81.5°), it will be cooled along line g_3 (Fig. 5) parallel to g_1 and g_2 and leave the 40 cooler at a temperature x (74.5°) which will be too high for use in the absorber-cooler unit because it has been found necessary to supply the cooling water with an initial temperature of about 71°, if the air is to be conditioned to the desired 45 dry bulb temperature of, say, 75°. The heat removed is equal in amount to that removed by the two circuits, but with the single circuit less heat is delivered to the air near the air exit end of the cooler—area H_{e2} becomes less—because of the 50 lower temperature gradients existing between water and air in that portion of the cooler. Additional heat is now delivered to the air near the entrance of the cooler—area H_{e1} is increased as much as H_{e2} is decreased—because of the increase 55 in temperature gradient there when a single water stream is used.

If conditions were chosen so a single stream of water was cooled to a minimum temperature of 71° in the cooler and it was cooled along line g_1 , 60 the initial temperature of this water would have to be that at z , or 78°, an impossible condition because no heat could be transferred to the air which at that point has a wet bulb temperature of 79.5°.

A similar analysis could be made of the values 65 graphically shown on the left side of Fig. 5 which sets forth conditions in the absorber-air conditioner unit.

Fig. 6 illustrates graphically representative results obtained when the apparatus and method of the invention are used to condition atmospheric air available at a dry bulb temperature of 81.5° F. and a wet bulb temperature of 65° F. These conditions provide a feeling of comfort in summer 75

to most people, but they cannot be maintained in air passing through an enclosure containing people and lights and a rise of about 6 degrees in both dry bulb and wet bulb temperatures of the air passing through the conditioner space is again assumed. The absorber-conditioner unit is operated so as to remove latent and sensible heat from the air while maintaining it at 40 percent relative humidity until the dry bulb temperature is 5 75° F. and the wet bulb temperature is 60° F. in anticipation of increments of heat which will be added to the air in the conditioned space.

This relatively small drop of 5 degrees in wet bulb temperature corresponds to the removal of 10 a rather small amount of heat which, in turn, requires but a small amount of water circulating in the cooling circuits or small temperature gradients across the walls of the coolers. The graphs in Fig. 6 reflect these conditions in that 15 water temperature lines g_4 and g_5 are closer to 20 and more nearly parallel line w_1 than were the corresponding lines on Fig. 5. And we now see that if the water in circuits 1 and 2 is combined in a single circuit and returned to the evaporative 25 cooler at a temperature z_1 (73.5° F.), it can be cooled along line g_4 to a temperature of 71° F., the temperature of the water in circuit 1. However, this result could not be obtained in a single 30 circuit under the more severe conditions of Fig. 5.

This application is a continuation-in-part of 35 my application Serial No. 73,026, filed April 6, 1936.

I claim:

1. The method which comprises bringing gas to 40 be supplied to an enclosure into contact with a moisture absorbing agent, removing heat from the 45 gas by indirect heat exchange with a heat transfer fluid supplying the gas to the enclosure, and thereafter contacting the gas leaving said enclosure with a stream of water which is in heat exchange relationship with said heat transfer fluid whereby the heat transfer fluid is cooled by 50 the evaporative cooling effect of the outgoing gas.

2. The method which comprises bringing gas 55 to be supplied to an enclosure into direct contact with a heat and moisture absorbing fluid which is in indirect heat exchange relation with a heat transfer fluid supplying the gas to the enclosure, and thereafter contacting the gas leaving said 60 enclosure with a stream of water which is in heat exchange relationship with said heat transfer fluid whereby the heat transfer fluid is cooled by the evaporative cooling effect of the outgoing gas.

3. The method which comprises absorbing 65 latent and sensible heat from a stream of air by contacting it with a heat and moisture absorbing fluid, while maintaining said fluid at a predetermined moisture absorptive capacity, passing said air through an enclosure, thereafter bringing said air into contact with a stream of water in an extended surface and thereafter bringing said stream of water into heat exchange relationship with said heat and moisture absorbing fluid.

4. The method which comprises contacting a 70 stream of air with a moisture removing agent, passing said air through an enclosure, thereafter transferring to said air successive increments of heat from a plurality of successive streams of heat transfer fluid by evaporation into the air of water in heat transfer relation with said streams and absorbing in said streams successive increments of heat from said stream of air before passing it through the enclosure.

75 5. The method which comprises absorbing

moisture from a stream of air by contacting it with a solid moisture absorbing agent, removing heat from the air by indirect heat exchange with a heat transfer fluid, supplying the air to an enclosure and thereafter contacting the air leaving 5 said enclosure with a stream of water which is in heat exchange relationship with said heat transfer fluid.

6. The method which comprises contacting a stream of air with a heat and moisture absorbing 10 fluid, passing said air through an enclosure, thereafter transferring to said air successive increments of heat from a plurality of successive streams of heat transfer fluid by evaporation into 15 the air of water in heat transfer relation with said streams, and absorbing in said streams successive increments of heat from said heat and moisture absorbing fluid, said streams being brought into heat transfer relation with said heat and moisture absorbing fluid in inverse order of 20 their temperature.

7. The method which comprises bringing air to be supplied to an enclosure into direct contact with a heat and moisture absorbing fluid which is in indirect heat exchange relationship 25 with a plurality of successive streams of heat transfer fluid decreasing in temperature in the direction of flow of the air, supplying the air to the enclosure, and contacting the air leaving said enclosure with an extended surface of water in 30 heat exchange relationship with said successive streams in the order of increasing temperature in the direction of the air.

8. Apparatus comprising means for contacting air passing into an enclosure with an extended 35 surface of a moisture absorbing agent, means for contacting air leaving the enclosure with an extended surface of water, and means comprising a fluid stream in indirect heat transfer relation with said moisture absorbing agent for transferring heat therefrom to said water in contact 40 with the air.

9. Apparatus comprising means for contacting air passing into an enclosure with an extended 45 surface of a moisture absorbing agent, means for maintaining the water absorptive capacity of said agent at a predetermined point, means for contacting air leaving the enclosure with an extended surface of water and means comprising a fluid stream in indirect heat transfer relation 50 with said moisture absorbing agent for transferring heat therefrom to said water in contact with the air.

10. Apparatus comprising a heat and moisture absorbing chamber and an evaporative cooling 55 chamber, means for causing a stream of air to flow successively through said absorbing chamber, an enclosure and said cooling chamber, means for contacting the air with an extended surface of a moisture absorptive agent in said 60 absorbing chamber, means for contacting the air with an extended surface of water in said cooling chamber, and means for circulating a heat transfer fluid in heat exchange relation with said water and in indirect heat exchange relation with the 65 air in said absorbing chamber.

11. Apparatus comprising a heat and moisture absorbing chamber and an evaporative cooling chamber, means for causing a stream of air to flow successively through said absorbing chamber, an enclosure, and said cooling chamber, means for contacting the air with an extended 70 surface of a moisture absorptive agent in said absorbing chamber, means for contacting the air with an extended surface of water in said cooling 75

chamber, and means for circulating a heat transfer fluid in heat transfer relation with said absorptive agent and said water.

12. Apparatus comprising a heat and moisture absorbing chamber including extended surface coils and an evaporative cooling chamber providing extended surfaces, means for causing a stream of air to flow successively through said absorbing chamber, an enclosure, and said cooling chamber, means for causing a moisture absorptive agent to flow over the coils in said absorbing chamber, means for causing a stream of water to flow over the extended surface in said cooling chamber and through the coils in said absorbing chamber.

13. Apparatus comprising a heat and moisture absorbing chamber including extended surface coils and cooling means including extended evaporative surfaces, means for causing a stream of air to flow successively through said absorbing chamber, an enclosure and said cooling means, means for effecting a circulation of moisture absorptive agent over the coils in said absorbing chamber, means for causing a stream of water to flow over the evaporative surfaces in said cooling means, and means for maintaining at least two separate streams of heat transfer fluid in circulation between said cooling means and said absorbing chamber, that stream which is in heat transfer relation with air of lowest wet bulb temperature in the cooling means being brought into heat transfer relation with air of lowest temperature in the absorbing chamber.

14. Apparatus comprising a heat and moisture absorbing chamber including extended surface coils and cooling means including extended evaporative surfaces, means for causing a stream of air to flow successively through said absorbing chamber, an enclosure and said cooling means, means for effecting a circulation of moisture absorptive agent over the coils in said absorbing chamber, means for causing a stream of water to flow over the evaporative surfaces in said cooling means, and means for maintaining at least two separate streams of heat transfer fluid in circulation between said cooling means and said absorbing chamber, that stream which is in heat transfer relation with air of lowest wet bulb temperature in the cooling means being brought into heat transfer relation with air of lowest temperature in the absorbing chamber and the said absorptive agent being circulated in parallel streams of heat transfer fluid in the absorption chamber.

15. Apparatus comprising a heat and moisture

absorbing chamber including extended surface coils and cooling means including extended evaporative surfaces, means for causing a stream of air to flow successively through said absorbing chamber, an enclosure and said cooling means, means for effecting a circulation of moisture absorptive agent over the coils in said absorbing chamber, means for causing a stream of water to flow over the evaporative surfaces in said cooling means, means for maintaining at least two separate streams of heat transfer fluid in circulation between said cooling means and said absorbing chamber, that stream which is in heat transfer relation with air of lowest wet bulb temperature in the cooling means being brought into heat transfer relation with air of lowest temperature in the absorbing chamber, and means for bringing additional air from an external source into contact with water in heat transfer relation with at least one of said streams of heat transfer fluid.

16. Apparatus comprising a heat and moisture absorbing chamber including extended surface coils and cooling means including extended evaporative surfaces, means for causing a stream of air to flow successively through said absorbing chamber, an enclosure and said cooling means, means for effecting a circulation of moisture absorptive agent over the coils in said absorbing chamber, means for causing a stream of water to flow over the evaporative surfaces in said cooling means, and means for maintaining at least two separate streams of heat transfer fluid in circulation between said cooling means and said absorbing chamber, that stream which is in heat transfer relation with air of lowest wet bulb temperature in the cooling means being brought into heat transfer relation with air of lowest temperature in the absorbing chamber and the said absorptive agent being circulated in parallel streams in countercurrent heat transfer relation with the streams of heat transfer fluid in the absorption chamber.

17. A method of removing heat and water vapor from air which comprises passing the air in contact with a succession of extended surfaces of a moisture-removing agent, while maintaining said agent at progressively lowered temperatures in the direction of flow of the air by indirect heat exchange with a plurality of streams of heat transfer fluid which are cooled to progressively lowered temperature levels by means of successive increments of the evaporative cooling effect of the treated air.
